UNITED STATES PATENT OFFICE.

OSCAR H. PIEPER AND ALPHONSE F. PIEPER, OF ROCHESTER, NEW YORK.

FUSE-HOLDER.

1,265,245.

Specification of Letters Patent.

Patented May 7, 1918.

Application filed September 27, 1915. Serial No. 52,936.

To all whom it may concern:

Be it known that we, OSCAR H. PIEPER and ALPHONSE F. PIEPER, of Rochester, county of Monroe, and State of New York, have invented certain new and useful Improvements in Fuse-Holders; and we do hereby declare the following to be a full, clear, and exact description of the same, reference being had to the accompanying drawings, forming a part of this specification, and to the reference-numerals marked thereon.

Our invention relates to fuse holders for electrical circuits, and has for its purpose to afford a simple structure that can be manufactured at a reasonable cost. A further object of the invention is to provide a device for the purpose mentioned which is strong, durable and efficient in every way, and capable of firmly maintaining a fuse in proper relation to the circuit in which it is disposed. To these and other ends the invention consists in certain improvements and combinations of parts, all as will be hereinafter more fully described the novel features being pointed out in the claims at the end of the specification.

In the drawings:

Figure 1 is a sectional view of a panel board, showing the application of the invention, with parts appearing in elevation;

Fig. 2 is an end elevation of the device;

Fig. 3 is a longitudinal sectional view on the line 3^a—3^a of Fig. 2;

Fig. 4 is a longitudinal sectional view on the line 4^a—4^a of Fig. 2, and

Fig. 5 is an end elevation looking toward the right of Fig. 4.

Similar reference characters throughout the several views indicate the same parts.

The present embodiment of the invention includes a conducting member preferably in the form of a metallic sleeve 1 adapted to be inserted in a wall or panel 2 and threaded at 3 to receive a protecting cap 4, while 5 designates an additional threaded portion on the sleeve to which may be attached a nut 6 having the conductor 7 connected thereto.

8 designates one of a plurality of resilient fuse engaging portions or arms, the inner ends of which are attached to the sleeve 1 in any suitable manner, as by means of rivets 9. Attached to the opposite end of the sleeve 1 is a support of insulating material preferably in the form of a sleeve, designated at 10, and secured by the rivets 11.

The support 10 also carries a plurality of

fuse engaging members, and to this end is provided with a conducting member designated generally 12, which has a pair of inwardly extending arms 13 attached to the support by means of rivets 14. The support 10 has at its outer end a plurality of longitudinally extending slots or openings 15, and 16 designates one of a plurality of yieldable fuse engaging members or arms carried by the conducting member 12 and extending inwardly within the openings 15 toward the end of the sleeve 1. The conducting member 12 also carries an enlargement 17 against which the fuse 18 engages, as shown in Fig. 70 3. The enlargement 17 is threaded internally at 19 to receive a screw 20, by which the conductor 21 is attached and held in place.

The location of a fuse when operatively positioned is shown in Fig. 3. In order to position the fuse it is inserted between the arms 8, and forced inwardly until it engages the arms 16 and the enlargement 17. The yieldable engaging members serve to hold 80 the fuse in rigid relation, and at the same time to maintain an unbroken circuit. The structure is inexpensive to manufacture and possesses considerable advantage accruing from the strength and durability of the device and the ease with which a fuse can be inserted or removed. It also possesses considerable utility in its applicability to panel boards in various types of electrical equipment, such as for instance are employed in 90 the control of dental apparatus where it is desirable to conceal the parts and at the same time permit ready accessibility to a fuse.

We claim as our invention:

1. A fuse holder comprising a conducting member, a plurality of yieldable engaging portions attached at one end thereof, a support of insulating material attached at the opposite end of said conducting member, and a plurality of yieldable fuse engaging members secured to the support.

2. A fuse holder comprising a conducting sleeve, a plurality of yieldable fuse engaging portions attached at one end thereof, a support of insulating material attached to the conducting sleeve and projecting beyond the opposite end thereof, and a plurality of yieldable fuse engaging members secured to the support.

3. A fuse holder comprising a conducting sleeve, a plurality of yieldable fuse engaging

- portions attached at one end thereof, a supporting sleeve of insulating material attached at the opposite end of the conducting sleeve, and a plurality of yieldable fuse engaging members secured to the supporting sleeve.
4. A fuse holder comprising a conducting sleeve, a plurality of yieldable fuse engaging portions attached to and extending beyond one end of the conducting sleeve, a support of insulating material attached to the conducting sleeve and projecting beyond the opposite end thereof, and a plurality of yieldable fuse engaging members secured to the support and projecting inwardly therefrom toward the conducting sleeve.
5. A fuse holder comprising a conducting member, a plurality of yieldable fuse engaging portions attached to and extending beyond one end of the conducting member, a support of insulating material attached to the conducting member and projecting beyond the opposite end thereof and having a series of slots or openings extending longitudinally from its outer end, and a plurality of fuse engaging members secured to the support and located in said slots.
6. A fuse holder comprising a conducting member, a plurality of yieldable fuse engaging portions attached to and extending
- beyond one end thereof, a support of insulating material attached to the conducting member and projecting beyond the opposite end thereof having a series of slots or openings extending longitudinally from its outer end, and a second conducting member arranged within the support and carrying a plurality of fingers located in said slots or openings and extending inwardly from the end of the support, forming resilient fuse engaging members.
7. A fuse holder comprising a conducting member threaded exteriorly at one end to receive a cap, a plurality of yieldable fuse engaging portions attached to the conducting member and extending beyond said end thereof, a support of insulating material attached at the opposite end of said conducting member, and a plurality of yieldable fuse engaging members secured to the support.
